Des. 2329

George T. Spicer, of Providence, R. I.
Letters Patent No. 2329 Dated May 9, 1866
Design for a Cooks Stove.

The schedule referred to in these Letters Patent and making part of the same

To all whom it may concern:

Be it known that I, George T. Spicer, of the City and County of Providence in the State of Rhode Island, having originated and designed a new pattern or design for cooking stoves a full, clear and exact description of which appears by the drawings hereto annexed and made part of this specification.

claim

What I claim as my invention and desire to secure by Letters Patent is the design or pattern for cooking stoves herein set forth and shown.

Witness,

Benj. N. Thompson
William E. Bowen,

150

George T. Spicer.
